UNITED STATES PATENT OFFICE.

WALTER H. KNIGHT, OF NEW YORK, N. Y.

ELECTRIC RAILWAY.

SPECIFICATION forming part of Letters Patent No. 447,332, dated March 3, 1891.

Application filed March 13, 1886. Serial No. 195,133. (No model.)

To all whom it may concern:

Be it known that I, WALTER H. KNIGHT, a citizen of the United States, and a resident of New York city, New York, have invented certain new and useful Improvements in Electric Railways, of which the following is a specification.

My invention relates to electric railways; and it consists in, first, a supplementary frame on the car or locomotive for supporting the motor and contact device, and, second, various features of construction of a conduit and contact device, whereby several important necessities in the construction and operation of a conduit system of electric railways are met.

It is illustrated in the accompanying drawings, wherein—

Figure 1 is a side elevation of the motor-supporting frame and the cleaning device. Figs. 2 and 3 are respectively transverse and longitudinal sections illustrating the railway-crossing, and Fig. 4 is a detail view illustrating the support of the motor.

In Fig. 1, D³ is a frame of steel or iron, resting directly upon the axles of the wheels and carrying the motor (shown conventionally at S) and plow E'. D³ represents the stringer of the car or cab, which is supported by springs S' from the frame D³. The springs are spiral springs placed adjacent to the journals of frame D³ upon the car-axle, and, as shown, surround guide pins or stirrups extending down from the stringer D³ of the car-body. The motor is inclosed in a casing D⁴, of canvas or like non-resonant material, and the grating above will permit its heat and that of the resistance-box to warm the car when desired. The motor is supported from the truck-frame D² by straps or side bars D⁵, passing under the motor, as in Fig. 4, and joining the longitudinal bars of the frame.

When one car is drawing another it has been found desirable that a broom or cleaning device for the conduit should be supported from the second car, so that the plow carried by the motor-car will not be spattered with mud and slush by the broom. The broom will be a splint broom and will have all the movements which are characteristic of the plow, as is set forth in my patent, No. 338,175, granted March 16, 1886.

The manner of carrying my conduit across

a railway-track is illustrated in Figs. 2 and 3. E is a yoke carrying at its upper edge one of the rails of the railway, and has a transverse opening permitting the passage of the conduit containing the conductors. E² is a regular railway-rail. E' is a removable special rail bolted to the yoke and interrupted at the slot. The two ends of rail E' at the slot are insulated, as shown at E⁴, because they extend into the conduit and are likely to come in contact with the plow as it passes through. The slot-rails R R of the conduit are also interrupted at the crossing, so as to receive the special rail E', and thus at the crossing-point there will be more or less open space through which water and mud are likely to drip from the street. The conductors F F' are just below the edge of E', and in order to prevent leakages from mud coming in at the crossing-point the conductors are preferably interrupted at that point by a length of insulating material E⁷, the break being bridged by E⁸. A double contact-plow will then be employed, so that the circuit to the plow will not be interrupted, one plow being on the break at a time. The plow and broom will both have a shank adapted to go between the two ends of E', and between E' and E² will be left a short break for the flange of the car-wheel, so that the plow will not be lifted by the wheel riding upon its flange in going over E². Between the ends of the slot-iron and rail E' will be a plate of spring-steel E⁵, which will cover the conduit beneath and at the same time will be readily depressed by the wheels of passing vehicles on the railway.

What I claim as my invention is—

1. The combination, with a car and its wheels, of a supplementary frame journaled on the axles supporting said car through intermediate springs and carrying an electric motor geared to said wheels.

2. The combination, with the axles and wheels of an electrically-propelled vehicle, of a supplementary motor-supporting frame journaled on the axles, and the car-body supported from said frame by springs at points adjacent to the journals.

3. The combination, in an electrically-propelled vehicle, of a motor-supporting frame resting directly upon the axles, with the springs adjacent to each axle-box bearing

upon said frame and the car-body supported upon said frame through the springs, as described.

4. The combination, in an electric-railway crossing, of a transverse railway-track rail having a break for the passage of the contact device, and an electric supply-conductor interrupted mechanically at the point below the break in the said rail, but electrically continuous through the bridging conductor.

5. The combination, in an electric-railway crossing, of an electric supply-conductor interrupted at a point below a transverse railway-track rail, a contact device adapted to travel along said conductor, and an insulated piece in the break adapted to carry over the contact device.

15 6. The combination, in an electric-railway

crossing, of an electric supply-conductor, a contact device, a transverse railway-track rail above said conductor interrupted to allow the passage of the contact device, and insulation upon the side of the break, whereby contact between said contact device and the rail is prevented.

7. The combination, with a slotted conduit of an electric railway, of a transverse track-rail E', interrupted at the slot and having its ends at the opening cut away on the lower edge to permit of a greater thickness of insulation between the ends of the rail and the passing contact-plow.

25 WALTER II. KNIGHT.
